UNITED STATES PATENT OFFICE.

HARRY G. EGBERT, OF DAYTON, OHIO.

DESIGN FOR A TIRE.

54,348.

Specification for Design.

Patented Dec. 30, 1919.

Application filed June 30, 1919. Serial No. 307,861. Term of patent 7 years.

To all whom it may concern:

Be it known that I, HARRY G. EGBERT, a citizen of the United States, residing at Dayton, in the county of Montgomery and State of Ohio, have invented a new, original, and ornamental Design for Tires, of which the following is a specification, reference being had to the accompanying drawing, forming part thereof.

Figure 1 is an edge view of a tire showing my design; Fig. 2 is a plan view of a portion thereof; and Fig. 3 is a cross sectional view.

I claim:

The ornamental design for a tire as shown.

HARRY G. EGBERT.
